Williams Woolley.

COLONIAL PATENT. (Patented May 13, 1833)

The subject is referred to in these Letters Patent, and making part of the same, containing a description in the words of the said Williams Woolley himself of his improvement in the construction of a Frize Window and Covering.

This improvement by putting a window in the frize under the cornice, is intended to avoid the necessity of resorting to the Dormer window, which is both expensive and inconvenient. The Frize window is an improvement invented by me several years since, and has since gone into very general use in good buildings in the city of New York, and elsewhere. In this window, I have made an improvement, and it is this improvement for which I ask a Patent, and it consists in covering it with a metallic or cast iron blind or shade, constructed in such a manner as to conceal the window, whilst it ornaments the frize of the cornice, and admits light and air sufficient for the room. For a house, having twenty-five feet front, the frize window should be about three feet six inches by twenty-two inches running lengthwise with the frize of the cornice, as shown in the drawing. This window may be varied in size, or proportion according to the size and situation of the other windows in the same front, and according to the taste of the Artist. The blind or shade is made just large enough to cover the opening made for the window and may be covered over, or let in according to the taste of the Artist. This blind is made in the best and cheapest manner of cast iron, but may be made of any other material. To let in light and air, all that part covering the opening left for the window is open work, carved and ornamented according to the taste of the Artist, or it may be made in open lattice work, of preferred. When put up it is well painted, and resembles the wood or frize of the cornice in which the window is inserted. This blind may be hung either as preferred. The drawing which accom-

specifications how fully the blind is to be applied to the window in the fringe. This iron blind may be made of cast iron and wrought iron, according to the fancy of the proprietor, may suggest and when finished and painted, will exactly resemble wood and be much more durable, and much cheaper. The above described blind, cast from iron or other material, and so constructed as to admit sufficient light and air, which it shades or shades the windows, and forms an elegant ornament in the fringe of the cornices. I claim as my invention and improvement,

In testimony whereof, I have hereunto set my hand and seal in the presence of two witnesses.
